UNITED STATES PATENT OFFICE.

HARRY T. KINGSBURY, OF KEENE, NEW HAMPSHIRE.

TOY LADDER-TRUCK.

1,229,975.

Specification of Letters Patent. Patented June 12, 1917.

Application filed July 22, 1916. Serial No. 110,758.

To all whom it may concern:

Be it known that I, HARRY T. KINGSBURY, a citizen of the United States, residing at Keene, in the county of Cheshire, State of New Hampshire, have invented certain new and useful Improvements in Toy Ladder-Trucks, of which the following is a description, reference being had to the accompanying drawing and to the figures of reference 10 marked thereon.

My invention relates to improvements in toy ladder trucks.

An object of my invention is to provide a ladder truck of this character driven by 15 a motor and in which the ladders are normally held in a horizontal position and are automatically raised, upon the forward end of the truck coming in contact with an obstacle and is held in said raised position 20 until lowered by hand.

A further object of my invention is to provide a ladder truck in which the ladder and its raising means are of a simple construction whereby the toy can be cheaply 25 manufactured and having certain details of structure and operation hereinafter more fully described.

In the accompanying drawings:—

Figure 1 is a side elevation of my toy 30 ladder truck showing the ladder sections in their lowered position;

Fig. 2 is a top plan view of Fig. 1;

Fig. 3 is a side elevation, showing the 35 ladder sections in their raised position; and

Fig. 4 is an enlarged sectional view of the hinge connection between the ladder sections.

Referring now to the drawings, 1 represents the frame of my improved truck which 40 is preferably of U-shaped form and supported at its rear end by the plate 2 secured to the upper face of the motor casing 3. The motor casing on its lower face is provided with ears in which the axle 4 of the 45 rear wheels 5 is mounted and said axle is driven by the motor, all of which is well understood and needs no further description.

The forward end of the U-shaped frame 50 2 is provided with the plate 6 having downwardly extending ears 7 in which is mounted the forward axle 8 carrying the wheels 9. While I have shown this specific form of frame for supporting the wheel, it will 55 be understood that the same could be varied without departing from the invention.

The forward end of the frame 1 is provided with a seat supporting frame 10 carrying the seat 11 and the steering column 12. The frame 10 has in rear of the seat 11 the upwardly extending ears 13 and 14 in which is mounted a shaft 16. Pivotaly mounted upon the shaft 16 is a ladder truck section 17 which is normally in a horizontal position and has its outer end resting upon the plate 2, as clearly shown in Fig. 1 of the drawings. Secured to the outer end of the ladder section 17 is a plate 18 which is provided with outwardly extending ears 19 in which is secured the shaft 20 and the plate having a tongue 21 bent around the rung 22 of the ladder section 17. 60 65 70

The outer ladder section 23 has a plate 24 secured to the inner end which has ears 25 through which the shaft 20 passes and by means of which the two ladder sections are pivoted together so that their ends 26 and 26' abut when the ladders are in their extended position as clearly shown in Fig. 3 of the drawings. The plate 24 has tongue 27 bent around the rung 28 of the ladder section 23 and whereby the plate is secured to the ladder section. 75 80

Pivotaly mounted upon the shaft 16 is a plate 29 which extends between the ears 85 13 and 14 and extends vertically a considerable distance above the ears. Slidably mounted upon the frame 10 is a wire loop 30 which has a reduced forward end 31 passing through a slot 31' in the frame 6. The rear end of the wire loop has its ends turned laterally at 32 and entering the bifurcated ends 33 of the plate 29 and whereby the plate is rocked upon the pivot for the purpose hereinafter more fully described. 90 95

Secured to the tongue 27 of the plate 24 is an L-shaped plate 34 which has secured thereto a coil spring 35 which has its opposite end secured to the plate 29 at the central cutaway portion at 36 as clearly shown 100 in Fig. 1 of the drawings. The spring 35 as shown normally is exerting a forward pressure on the upper ladder section 23 which holds the rung 37 in the notches 38 of the bifurcated upper end of the plate 29 105 and whereby said upper and lower sections are held in a horizontal position.

In the operation the truck is driven by the motor and upon the looped end 31 of the loop 30 striking an obstacle such as the 110 wall or the like, forces the loop 30 rearwardly rocking the plate 29 on the pivot

- 16 forcing the upper end carrying the notches away from the rung 37 and releasing the same. The spring 35 draws on the L-shaped plate 34 and the same being fulcrumed on the shaft 20 forces the outer ladder section 23 upwardly and outwardly into a position approximately horizontal. After reaching this position the L-shaped plate 35 bears upon the plate carried by the ladder section 17 and throws the ladder section 17 into an approximately vertical position as shown in Fig. 3 of the drawing. It is understood that the ladder is moved downward and latched by hand.
- 15 It is obvious that minor changes in the details of construction and arrangement of parts, should be made without departing from the spirit of the invention as set forth in the appended claims.
- 20 Having thus described my invention, what I claim as new and desire to secure by Letters Patent, is:—
1. A toy ladder truck, comprising a ladder pivoted thereto and formed of pivotally connected sections, a catch for holding the ladder sections in their folded horizontal position, and a spring connected to the inner end of the outer section below its pivot and normally holding the sections in their extended vertical position.
- 25 2. A toy ladder truck, comprising a ladder pivoted thereto and formed of pivotally connected sections, a catch for holding the ladder sections in their folded horizontal position, and a spring connected to the latch and the inner end of the outer ladder section below its pivot with the other section and normally holding the sections in their extended vertical position.
- 30 3. A toy ladder truck, comprising a ladder pivoted thereto and formed of pivotally connected sections, an intermediately pivoted catch engaging the rung of the outer section of the ladder and holding the sections in their folded horizontal position, and a spring normally holding the sections in their extended vertical position.
- 35 4. A toy ladder truck, comprising a ladder pivoted thereto and formed of pivotally connected sections, an intermediately pivoted catch engaging the rung of the outer section of the ladder and holding the sections in their folded horizontal position, a spring normally holding the sections in their extended vertical position, and means for releasing the catch and extending beyond the forward end of the truck.
- 40 5. A toy ladder truck comprising a ladder pivoted thereto and formed of pivotally connected sections, a catch for holding the ladder sections in their folded horizontal position, and a spring connecting the inner end of the outer section below the pivot and the catch and normally holding the sections in their extended vertical position.

6. A toy ladder truck comprising a ladder pivoted thereto and formed of pivotally connected sections, a catch for holding the ladder sections in their folded horizontal position, and a spring connected to the latch and the inner end of the outer ladder section and normally holding the sections in their extended vertical position.

7. A toy ladder truck comprising a ladder pivoted thereto and formed of pivotally connected sections, a catch adapted to engage the rung of the outer ladder section and holding the sections in their folded horizontal position a spring connected to the latch and the inner end of the outer ladder section and normally holding the sections in their extended vertical position.

8. A toy ladder truck comprising a ladder pivoted thereto and formed of pivotally connected sections, a catch adapted to engage the rung of the outer ladder section and holding the sections in their folded horizontal position, a spring connected to the catch and the inner end of the outer ladder section and normally holding the sections in their extended vertical position, and a member extending beyond the end of the truck for tripping the latch and releasing the outer section whereby the spring draws the ladder section upwardly in a vertical position.

9. A toy ladder truck comprising a ladder pivoted thereto and formed of pivotally connected sections, a vertically disposed catch adjacent the pivot of the ladder and having notches to receive the rung of the outer ladder section and hold the sections in their folded horizontal position, a spring connected at one end to the catch and the opposite end connected to the inner end of the outer section and adapted to throw the same outwardly and draw the sections in a vertical aligned position, and a sliding member connected to the catch and extending beyond the truck whereby the engagement of the sliding member with an obstacle will move the latch forward releasing the outer section of the ladder and the spring will throw the ladders in their extended vertical position.

10. A toy ladder truck, comprising a frame, a ladder pivoted to the forward end of the frame and formed of pivotally connected sections, a vertically disposed catch intermediately pivoted on the pivot of the ladder and having notches to receive the rung of the outer section and hold the sections in their folded horizontal position, a spring connected to the catch below the notches and the opposite end connected to an L-shaped plate carried by the inner end of the outer section and said spring adapted to throw the same outward and draw the sections forward in a vertical aligned position and a sliding member connected to the lower end of the catch and extending beyond

the truck whereby the engagement of the sliding member with an obstacle will move the catch forward releasing the outer section and allowing the spring to throw the ladder sections in their extended vertical positions.

5 11. A toy ladder truck, comprising a ladder pivoted thereto and formed of pivotally connected sections, an intermediately pivoted catch engaging the outer section of the ladder for holding the sections in their folded horizontal position, a spring connected to the inner end of the outer section and the catch above its pivot, and means connected to the catch below the pivot and extending 10 beyond the forward end of the truck.

15 12. A toy ladder truck, comprising a ladder pivoted thereto and formed of pivotally connected sections, an intermediately pivoted catch engaging the outer section of the ladder for holding the sections in their folded horizontal position, a spring connected 20 to the outer section and to the catch above its pivot, and means extending beyond the forward end of the truck and engaging the latch below its pivot whereby the catch is released.

25 13. A toy ladder truck, comprising a ladder pivoted thereto and formed of pivotally connected sections, an intermediately pivoted catch engaging the outer section of the ladder for holding the sections in their folded horizontal position, a spring connected to the inner end of the outer section below the pivot and the catch above the pivot, and means connected to the catch below the pivot and extending beyond the forward end of the truck.

18. A toy ladder truck, comprising a ladder pivoted thereto and formed of pivotally connected sections, an intermediately pivoted catch engaging the outer section of the ladder for holding the sections in their folded horizontal position, and a spring connected to the inner end of the outer section and the catch above its pivot.

30 14. A toy ladder truck, comprising a ladder pivoted thereto and formed of pivotally connected sections, an intermediately pivoted catch engaging the outer section of the ladder for holding the sections in their folded horizontal position; a spring connected 35 to the outer section and to the catch above its pivot, and means extending beyond the forward end of the truck and engaging the latch below its pivot whereby the catch is released.

40 45 In testimony whereof, I affix my signature in the presence of two witnesses.
